UNITED STATES PATENT OFFICE.

JOSEPH G. ZIMLICH, OF CLEVELAND, OHIO.

BARREL-RACK.

1,312,150.

Specification of Letters Patent.

Patented Aug. 5, 1919.

Application filed August 21, 1917. Serial No. 187,451.

To all whom it may concern:

Be it known that I, JOSEPH G. ZIMLICH, a citizen of the United States, residing at Cleveland, in the county of Cuyahoga and

5 State of Ohio, have invented a certain new and useful Improvement in Barrel-Racks, of which the following is a full, clear, and exact description, reference being had to the accompanying drawings.

10 This invention relates to barrel racks and particularly to barrel racks for lifting barrels and such like from the floor and transporting the same to places for the removal of the contents thereof. The objects of the 15 invention are the provision of tilting and elevating devices of this sort whereby the barrel may be quickly and easily lifted from the floor and positioned in a horizontal position upon the apparatus with a minimum 20 expenditure of time and labor; the provision of means whereby the barrel may be taken from the floor and removed in a more efficient and rapid manner than has heretofore been possible; the provision of a balanced 25 rack which one man may handle with ease and facility; and the provision of a rack embodying a minimum of parts of simple and standard construction whereby the cost 30 of production and manufacture thereof is reduced to a minimum.

For a better understanding of the advantages and novel features of my invention reference may be had to the drawings accompanying this application in which 35 Figure 1 is a side elevation of the rack and a barrel resting thereon; Fig. 2 is an end view thereof; and Fig. 3 is an end view of a modified construction.

Referring to the drawings where like 40 numerals refer to similar parts throughout, my novel rack comprises a standard denoted generally by the numeral 1 and a cradle 2 having a horizontal shaft 3 journaled in bearings 4 carried by the top of the stand- 45 ard 1. The standard 1 comprises two pairs of side members 5 and 6, the members of each pair being inclined toward each other and bridged at their top by a horizontal member 7. The lower ends of each pair of 50 side members 5 and 6 are bridged by the

angle irons 8, these being secured thereto in any convenient manner as by means of rivets. The rear members of the pairs 5 and 6 are fixed together and braced into a rigid structure by means of cross pieces or strips 55 9, one of these pieces being slightly bent as indicated at 10 in Fig. 1 to clear the other member at the crossing point. Just above these cross strips 9 is located the horizontally disposed angle iron 11 which also 60 bridges the rear members 5 and 6, it being understood that these members 9 and 11 are secured in any suitable manner to the side members 5 and 6 as by means of rivets. The bearings 4 comprise angle pieces which are 65 mounted in any suitable manner upon the top members 7 of the standard to receive the horizontally disposed shaft 3. The standard is adapted to be rolled about on the floor surface by means of two pairs of rollers or casters 12 and 13, the pair of rollers 12 being mounted on the bottom of the rear ends of the horizontal side members 8 and the pair of rollers 13 being mounted beneath the forward ends thereof. To the rearward 70 of the forward end of the standard there is disposed a cross piece 14 comprising an angle iron which is horizontally disposed and carried by the side angle irons 8. This serves as a bracer for the forward end of 75 the standard and also for another purpose hereinafter set forth. The cradle 2 comprises the two side members 15 whose top edges are curved in the manner indicated to conform to the contour of the barrel or other 80 article to be lifted and transported. At either end of this pair of side beams 15 is disposed a cross member 16, these members 85 16 also having their upper edges curved longitudinally thereof to conform to the 90 contour of the barrel, in this case the curvature corresponding to the arc of a circle. These cross members 16 may be secured to the side members 15 in any suitable manner as by bolts indicated at 17. The shaft 3 is 95 journaled in the side members 15 at a point substantially midway of their lengths as indicated in the drawing. The forward ends of the side members 15 of the cradle are tapered as indicated at 18, this being for a 100

purpose hereinafter set forth, and on each tapered end is disposed an upturned ear or lug 19 which are secured to the side members 15 in any suitable manner. On the rear-
 5 ward side of the forward cross piece 16 is fixed a bracket 20 and this bracket 20 carries pivotally attached thereto a locking arm 21, this arm being pivoted to the bracket 20 for movement in a vertical plane. This
 10 locking arm 21 has provided on its free end a notch or latch 22 which is adapted to coöperate with the cross angle iron 14 to automatically latch or lock the cradle 2 in the horizontal position as indicated in Fig.
 15 1, the angle iron 11 which is located on the rear end of the standard being adapted to engage the side members 15 of the cradle and thereby limit the movement of the cradle below the horizontal in a backward
 20 direction.

Fig. 1 shows in dotted lines the position of the parts when the barrel is being engaged preparatory to positioning the same on the cradle and raising the same to a
 25 horizontal position, the barrel being indicated at 23. When it is desired to lower a barrel from the cradle 2 or to pick up a barrel which is resting on its head on the floor the operator kicks the free end of
 30 the locking arm 21 free from the cross piece 14 and then gradually lowers the forward end of the cradle 2 on the shaft 3 as a pivot to the dotted position shown. In this position the tapered ends 18 of the side members 15 are brought in between the forward side members 5 and 6 and into engagement with the floor, the cross member 14 being far enough back to permit this operation. The tapered feature of these ends permits
 35 the ears 19 to approach the surface of the floor and in this position these ears or lugs may be inserted beneath the edge of the barrel by simply tilting the barrel slightly away from the rack, the ears in this position being substantially in alinement with the floor.
 40 After the positioning of the lugs 19 beneath the barrel 23, the same may be swung over against the cradle 2 and since the tapered ends 18 are at all times during this operation in engagement with the floor the rack is prevented from rolling in a backward direction. After the barrel is brought into engagement with the inclined or substantially vertical cradle (illustrated in dotted
 45 lines) any further force applied to the upper end of the barrel tends to turn the cradle on the shaft 3 as a pivot without causing any pronounced backward movement of the rack, the balancing of the different parts of the
 50 rack bringing about this result. The angle iron 11 arrests the backward tilting movement of the cradle when the cradle and the barrel reach a substantially horizontal position. The locking arm 21 upon the for-
 55 ward tilting movement of the forward end

of the cradle rides, as is indicated in dotted lines, upon the cross piece 14 and in like manner on the return of the cradle to the horizontal position it continues to ride freely thereon, due to the free pivotal movement 70 thereof on the cross piece 14, and when the barrel and the cradle have reached the horizontal position the arm 21 automatically comes into operative engagement with the cross-piece 14 to lock or latch the barrel and 75 the cradle in the horizontal position.

In the modified structure shown in Fig. 3 the cross pieces 16 are obviated and in their place are positioned a pair of tie rods 24, these rods 24 passing transversely through 80 the side members 15' of the cradle and being secured thereto by nuts 25. The locking arm 21' is loosely mounted on the forward one of these tie rods 24 and may be positioned at any point desired along the rod. 85

The rack herein set forth may be manufactured and assembled at a greatly reduced cost of production as compared with racks of the prior art, this being due to the few parts embodied in the completed rack, the 90 simple nature thereof, and the standard construction of each of them, whereby the rack may be built from the material obtainable on the market without the necessity for special hand or machine work. The special 95 arrangement and exact proportions of the different parts result in a peculiarly well balanced rack which is easily manipulated.

Having thus described my invention, what I claim is:—

1. In an apparatus of the character described, the combination of two pairs of side frames, the rear ends of said frames being bridged by a horizontal stop member in substantial alinement with the upper edges of 105 said side frames, the bottoms of said frames being bridged by an angle iron at points removed from the forward ends thereof, a cradle comprising two side girders having cross pieces at the ends thereof, said girders 110 being journaled substantially midway of their lengths on bearings carried by the top of said frames and having their forward ends tapered for engagement with the floor when tilted, the forward ends of said frames 115 being adapted to receive therebetween and against said angle iron the forward ends of the girders when tilted, and a locking arm freely pivoted to the forward cross pieces of said girders and having a notch at its free 120 end for coöperation with said angle iron as a latch for automatically locking said cradle when returned to a horizontal position.

2. In an apparatus of the character described, the combination of two side frames 125 a stop member supported by the frames in substantially the plane of the upper edges thereof, a cradle comprising two side girders having cross pieces at the ends thereof, said girders being journaled substantially mid- 130

way of their lengths on bearings carried by the tops of the side frames, and a locking element pivoted to the cradle on the side of the journal thereof opposite the side whereon the aforesaid stop member is situated, the frames supporting a member having, with the locking element, coöperating parts

that are adapted to interlock for holding the cradle in a substantially horizontal position.

10

In testimony whereof I hereunto affix my signature.

JOSEPH G. ZIMLICH.
